UNITED STATES PATENT OFFICE.

CHARLES E. AKERS AND FRED WILSON, OF DECATUR, ILLINOIS.

DRAFT ATTACHMENT FOR VEHICLES.

SPECIFICATION forming part of Letters Patent No. 731,331, dated June 16, 1903.

Application filed April 8, 1903. Serial No. 151,673. (No model.)

To all whom it may concern:

Be it known that we, CHARLES E. AKERS and FRED WILSON, of the city of Decatur, in the county of Macon and State of Illinois, have 5 invented certain new and useful Improvements in Draft Attachments for Vehicles, of which the following is a specification.

This invention relates to doubletrees provided with bow-shaped springs which act as buffers and relieve the team from sudden variations in stress attendant on striking abrupt obstructions.

The object of the invention is to provide improved and simplified means for attaching 15 the spring to the doubletrees.

The invention is exemplified in the structure hereinafter described, and it is defined in the appended claims.

In the drawings forming a part of this specification, Figure 1 is a plan of a doubletree provided with a buffer-spring secured in place in accordance with our idea. Fig. 2 is an enlarged fragment of a doubletree and buffer-spring, parts of the spring and the doubletree being broken away to show the means used to connect the spring to the doubletree. Fig. 3 is a face or flatwise view of an end of the spring. Fig. 4 is a face view of a bearing-plate against which an end of the spring 25 slides while the spring is in action. Fig. 5 is a detail of the head end of the securing-bolt.

A fragment of a tongue is shown at 1 in Fig. 1, a hammer-strap at 2, and a hammer-bolt at 3. The doubletree is shown at 4, and 35 the buffer-spring is shown at 5. The spring has a loop-strap 8 at its center, which forms a bearing to encircle the hammer-bolt, and the ends of the spring have slots 5^a. Bearing-plates 6 have central holes 6^a, as shown 40 in Fig. 4. They are preferably circular, and they fit against the front surface of the doubletree between the doubletree and the ends of the spring. Bolts 7 have enlarged heads 7, and between the heads and the bodies of the 45 bolts are formed enlargements 7^b, which are preferably square in cross-section. The threaded ends of the bolts are provided with washers 9 and nuts 10. The enlargements 7^b of the bolts correspond in diameter with 50 the width of slots 5^a in the ends of the spring, and they are slightly longer than the thickness of the ends of the spring. The holes

6^a in bearing-plates 6 are smaller than the width of slots 5^a, and they correspond with the diameter of the bolts.

In securing the spring to the doubletree holes are made through the doubletree of proper size and in proper positions to receive bolts 7^a. The bearing-plates and the spring are placed against the doubletree. The bolts 60 are inserted through the slots of the spring, the holes of the bearing-plates, and the holes in the doubletree. The washers 9 are put in place, and the nuts 10 are tightened against the washers. When the spring is properly 65 secured to the doubletree, the plates 6 form cheap and simple bearing-surfaces against which the ends of the spring may slide. The square enlargements form guides on which the ends of the spring may move freely without binding. The enlarged heads 7 hold the 70 springs from moving off the guides, and the nuts and washers secure everything in place. The bearings for the ends of the spring permit the spring to move toward and from the doubletree without cramping the thin ends of the 75 spring and developing therein a movement that must ultimately result in breakage. The bearing-plate is held in place by the single 80 bolt, for the reason that the hole is central and the plate circular. No matter how much the plate may turn it will still retain its proper operative position. The bearing-plate performs the double function of providing a 85 slide-bearing for the spring and aiding the nut and washer in clamping the bolt to the doubletree. The enlargement of the bolt provides a bearing for the spring-slot and retains the bearing-plate in place against the doubletree. It also by its length holds the 90 head from contact with the spring, and when it is square in cross-section the spring-slot forms a wrench to hold the bolt against turning while the nut is tightened.

We claim—

1. The combination of a doubletree, a bow-shaped buffer-spring having its ends slotted longitudinally, a bolt having a short enlargement between its head and its body, said enlargement being slightly longer than the thickness of the ends of the spring and corresponding in diameter with the width of the slots of the spring and a bearing-plate having a hole large enough to receive the bolt and

smaller than the enlargement of the bolt; the bolt secured to the doubletree with the bearing-plate held against the doubletree by the enlargement of the bolt and the enlargement 5 engaging a slot of the spring.

2. The combination of a doubletree, a bow-shaped buffer-spring having its ends slotted longitudinally, a bolt having a short enlargement between its head and its body, said enlargement being slightly longer than the thickness of the ends of the spring and corresponding in diameter with the width of the 10 slots of the spring and a circular bearing-plate having a central hole large enough to

receive the bolt and smaller than the enlargement of the bolt; the bolt secured to the doubletree with the bearing-plate held against the doubletree by the enlargement of the bolt and the enlargement engaging a slot of the 15 spring.

In testimony whereof we sign our names in the presence of two subscribing witnesses.

CHARLES E. AKERS.
FRED WILSON.
